(57) **CLAIM**

The ornamental design for a tap, as shown and described.

DESCRIPTION

FIG. 1 is a perspective view of a tap.

FIG. 2 is a top plan view of the tap of FIG. 1.

FIG. 3 is a bottom view of the tap of FIG. 1.

FIG. 4 is a right side view of the tap of FIG. 1.

FIG. 5 is a left side view of the tap of FIG. 1.

FIG. 6 is a front view of the tap of FIG. 1; and,

FIG. 7 is a rear view of the tap of FIG. 1.

The lighter solid lines denote surfaces and contours. Line shading is not surface ornamentation.

The features of the tap shown in broken lines form no part of the claimed design.

1 Claim, 7 Drawing Sheets
